CLAIM

The ornamental design for an electrical connector housing, as shown and described.

DESCRIPTION

FIG. 1 is a perspective view of an electrical connector housing showing my new design;

FIG. 2 is a front elevational view thereof;

FIG. 3 is a top plan view thereof;

FIG. 4 is a rear elevational view thereof; and

FIG. 5 is a side elevational view thereof.

The sockets are partially shown in FIG. 1 for convenience of illustration, it being understood that the sockets would normally appear as shown in FIG. 2.
